CLOSURE FOR SUBMERSIBLE PUMPING UNITS

Lloyd Yost, Los Angeles, Calif., assignor to A. O. Smith Corporation, Milwaukee, Wis., a corporation of New York

Application March 24, 1941; Serial No. 384,882

8 Claims. (Cl. 172—36)

This invention relates to a closure for the upper end of submersible pumping units.

Pumping units of the kind here under consideration have an electric motor receiving electrical energy through a cable and are designed to be submerged in the liquid to be pumped, usually in an oil or other well.

One of the objects of the invention is to provide a closure for the upper end of such a unit with an improved seal between the cable and the unit.

Another object of the invention is to provide a closure which is readily assembled and which effectively protects the electric motor and other parts of the mechanism from damage by entrance of the liquid being pumped.

These and other objects of the invention will be clear from the following detailed description and the accompanying drawing in which:

Figure 1 is a vertical section through the upper end of a pumping unit constructed in accordance with the invention; and

Fig. 2 is a similar view showing the relative positions of the parts before the assembly is completed.

In accordance with the invention in its principal phase a separate chamber is provided between the end of the motor chamber and the end of the housing for receiving the end of the electric cable and its several separate conductors, the chamber being sealed from the motor chamber and from the outside to prevent fluid from injuring either the end of the cable or the conductors.

Referring to the drawing, and at first to Figure 1 which shows the parts assembled, the electric motor 1, preferably a three phase induction motor, has a stator 2 in a fluid tight shell 3 joined by weld 4 to a concentric sleeve 5. The upper bearing 6 for rotor 7 is held in a bearing support 8 which is secured in position by a snap ring 9 seated in a groove 10 cut in sleeve 5.

By means of mechanism which is housed in the lower part of the pumping unit, but which forms no part of this invention and is not shown in the drawing, the motor drives a pump which takes liquid from the well and forces it upward in the annular space between the outer casing or housing 11 and the inner assembly consisting of the motor shell 3, sleeve 5, and the other parts secured to them.

The motor leads 12 are soldered to tapered conducting pins 13 secured in a block 14 of Bakelite or other suitable material so as to form a fluid tight joint with the block. A spacer sleeve 15 extends upward from snap ring 9 to abut against the lower end of a packing ring 16 which may be

made of neoprene or other material resistant to the action of oil and suitable for packing. A shoulder 17 on molded block 14 is forced against the upper end of the packing ring 16 by an externally threaded clamping ring 18 which engages internal screw threads 19 in sleeve 5. The resultant compression of packing ring 16 between sleeve 5 and molded block 14 effectually seals the motor compartment against entrance of liquid from the outside and prevents the escape of gas from the motor compartment. A threaded locking ring 20 is provided to lock the clamping ring 18.

A short sleeve 21 is screwed into threads 19 in sleeve 5 to make an oil tight joint and is welded at its upper end to head 22. The electric cable 23 passes into the head through packing compressor 24, packing rings 25 of neoprene or other suitable material, and washers 26. A small passageway 27 extends from between the packing rings to the outside of the head. This passageway permits the escape of air trapped between the packing rings 25 when the packing compressor 24 is screwed into threads 19 to compress the packing rings and form a liquid tight seal between the cable and head. The passage 27 may also be used in testing the packing against leakage by applying through the passage an air pressure of sufficient magnitude, usually about 500 lbs. per square inch.

After the seal has been made by compressing the packing, the passageway is plugged with a plug 28 which may in addition be welded over to insure against leakage. The seal formed around the cable prevents leakage of oil into the head along the cable. Inside the head the cable separates into its constituent conductors 29 which are soldered or otherwise electrically connected to pins 13.

The annular space between the head 22 and outer casing 11 is sealed by means of a ring 31, packing rings 32, washers 33, and packing compressor 34. Ring 31 is secured against longitudinal movement by means of screws 35 passing through the outer casing 11 and welded over to prevent leakage. The packing rings 32 are compressed between the head and casing by screwing the packing compressor 34 into threads 36 in the end of the casing.

Oil that has been pumped by the unit from the well into the annular space between the inner assembly and outer casing 11 passes into head 22 through opening 37 and then into the tubing 38 which conveys it upward through the well.

The manner in which the assembly is made will be clear from Fig. 2. When the motor assembly is complete and the parts that are to go below it are secured in place, spacer sleeve 5 and packing ring 16 are inserted in sleeve 5 and the motor leads 12 are brought out beyond the end of the sleeve where they can readily be soldered to pins 13. A length of tubing 38 is screwed into head 22 and additionally secured, if desired to insure against leaks at the threaded joints, by weld 39. The cable 23 is entered into the head, sealed as previously described, and the end of the cable where the conductors are separated is taped or finished in any appropriate fashion as indicated at 40.

The means used to seal the annular space between the head and outer casing are positioned about as shown and the conductors from the cable are then passed through sleeve 21, locking ring 20, and clamping ring 18, and soldered or otherwise electrically connected to pins 13. It will be clear from the drawing that sufficient space is available to permit this to be readily done.

The molded block 14 is then seated in sleeve 5 with its shoulder 17 engaging packing ring 16. Clamping ring 18 and locking ring 20 are screwed home to close the upper end of the motor compartment and complete the first seal designed to prevent leakage into or out of the motor chamber. Sleeve 21 is then screwed into sleeve 5 to make an oil tight joint with the tapered end of sleeve 5 seated against the correspondingly tapered surface on sleeve 21. As the sleeve 21 has not yet been welded to head 22 it is clear that the threaded joint can be made up without twisting conductors 30.

The head 22 is then welded to sleeve 21 by weld 41. This completes the upper end of the inner assembly. It will be seen that the cable is packed where it passes through the head so as to prevent oil leakage along the cable, and that, in addition, the block 14 separates the space immediately below the head from the motor compartment. If either joint fails while the other remains tight, the motor compartment is effectively protected against the entrance of oil. It is only when both fail that oil can leak into the motor or gas escape in undesirable quantities.

The lower sections of the inner assembly that are to be connected below the motor are secured in place, if this has not previously been done, and the entire inner assembly is slipped into outer casing 11. The lower ends of the casing and inner assembly are joined by means which form no part of this invention.

The upper end of the annular space between the casing and inner assembly is then packed. Ring 31 is slipped down and secured by screws 35 through the outer casing which may be welded over on the outside to prevent leakage of oil. Packing rings 32 and washers 33 are put in position and packing compressor 34 is screwed down to compress the packing rings and form a fluid tight seal.

The head 22 and block 14 provide a sealed compartment between them and in which the end of cable 23 is broken down into the flexible leads 30. By reason of the sealing of this compartment there is no danger of the compressed gas or liquid in the motor compartment escaping and entering the end of the cable, and there is also no danger of fluid entering the compart-

ment from the outside and deteriorating the insulation on the leads 30.

I claim:

1. In a device of the class described, an electric motor, a cylindrical sleeve encasing the motor and providing a motor compartment, flexible electrical leads of substantial length extending from the end of the motor, an insulating block closing said sleeve and substantially spaced from the end of the motor, a packing ring disposed in compression to seal the joint between said block and sleeve, means to secure said block in place, a head spaced from said block and welded to the end of said sleeve to close the same and having an opening therein for receiving an electrical cable, packing means for sealing said cable in said opening, said cable having flexible leads of substantial length on its inner end, and means extending through said block for connecting the respective motor leads to the corresponding cable leads for supplying the motor with electricity, the flexibility of the leads serving to facilitate assembly of the block and head after connection of the leads, and the several seals serving to prevent leakage of fluid either into or out of the motor compartment in said sleeve.

2. In a device of the class described, a tubular casing, a motor compartment therein, means for sealing the end of said compartment in said casing against escape of fluid therefrom, a head closing said casing and providing a second compartment between the head and the end of said motor compartment, a cable extending through said head and sealed therein to prevent leakage of fluid from the outside into said second compartment, and flexible leads at the inner end of said cable in said second compartment making connections through the end of said motor compartment with corresponding leads from the motor to supply electricity thereto.

3. In a device of the class described, a motor compartment, a second compartment at the end thereof and having an electric cable extending into the same, the end of said cable being separated into its constituent leads in said second compartment, means connecting said cable leads to corresponding leads from the motor, and means sealing said second compartment to make the same fluid tight.

4. In a submersible pumping unit, a head, an electric cable passing through the head, packing rings in an annular space between the head and cable, screw threaded means to compress the packing rings and form a fluid tight seal between the head and cable, a passageway extending from between the packing rings to the outside of the head to provide for the escape of air as said packing rings are compressed during assembly, and means to plug the passageway after the packing rings have been compressed.

5. In a submersible pumping unit, an electric motor in a tubular container, motor leads electrically connected to electric conductors extending through an insulating block in fluid tight contact therewith, packing means to form a fluid tight joint between the block and the tubular motor container, a sleeve, a threaded joint between the sleeve and motor container, a head welded to the sleeve, an electric cable extending through the head with conductors electrically connected to the conductors passing through the insulating block, packing rings in an annular space between the head and cable, and screw threaded means to compress the packing rings

and form a fluid tight seal between the head and cable.

6. In a submersible pumping unit, a motor chamber, an insulating block closing the end of said chamber and having an oil resistant rubber packing sealing the same, metallic electrical connectors passing through said block and secured therein, motor leads secured to said connectors on the inside of said block, and an external supply cable secured to said connectors on the outside of said block.

7. In a submersible pumping unit, a motor chamber, an insulating block closing the end of said chamber, and a plurality of tapered pins of electrically conductive metal fitting and secured in correspondingly tapered openings in said block and extending therethrough for connecting an external supply cable to the motor leads.

8. In a submersible pumping unit, an electric

20

motor in a tubular container, motor leads electrically connected to electric conductors extending through an insulating block in fluid tight contact therewith, packing means to form a fluid tight joint between the block and the tubular motor container, a sleeve extension for the container, a threaded joint between the sleeve and motor container, a head welded to the sleeve, an electric cable extending through the head with conductors electrically connected to the conductors passing through the insulating block, packing rings in an annular space between the head and cable, screw threaded means to compress the packing rings and form a fluid tight seal between the head and cable, a passageway extending from between the packing rings to the outside of the head to permit escape of entrapped air when the packings are compressed, and means to plug the passageway.

LLOYD YOST.
